MAURICE M. KASANOF, OF BROOKLYN, NEW YORK.

DEVICE FOR STEAMING AND FOR STRETCHING OR SHRINKING TUBULAR FABRICS.

Application filed August 17, 1925. Serial No. 50,805.

My invention relates to the steaming and stretching of tubular fabrics and has particular advantages in the steaming and stretching of knitted tubular fabrics. With present methods of stretching and steaming tubular fabrics, the fabric is distorted to an objectionable degree and this is especially true of tubular fabrics having designs involving transverse stripes or bars. The usual methods employed stretch the fabric unevenly at different places and as a consequence with tubular fabrics having designs presenting transverse members, the members are distorted so that they no longer extend straight across and in parallel relation but assume more or less of a curved condition.

The general object of my invention is to provide a steaming and stretching device that will result in a uniform stretching of fabric without any distortion of the design presented by the fabric, and the use of which device will result in uniform friction between the tubular fabric and the device as the fabric is drawn over said device.

A further object of my invention is to provide a steaming and stretching device for tubular fabrics which will possess increased efficiency and which may be employed with marked facility in the steaming and stretching of the fabric and which may be employed for shrinking fabric.

The nature of my invention and its distinguishing features and advantages will clearly appear as the description proceeds.

Reference is to be had to the accompanying drawings forming a part of this specification, it being understood that the drawings are merely illustrative of one example of the invention.

Figure 1 is a side elevation of a stretching and steaming device embodying my invention;

Figure 2 is an enlarged transverse vertical section in a plane indicated by the line 2-2, Figure 1;

Figures 3 and 4 are cross sections respectively on the lines 3-3 and 4-4, Figure 2.

In carrying out my invention in practice, in accordance with the illustrated example, a tubular standard 10 is provided and supported thereon is a steam supply pipe 11. The standard 10 may be given support from a floor, table, or the like in any approved manner. The supply pipe 11 is here shown

as a cross pipe disposed transversely of the standard 10. The numeral 12 indicates the steam inlet pipe in which is a suitable shut-off valve 13. The steam supply pipe 11 has connected therewith an elongated element 15. The element 15 advantageously in practice is in the form of a steam pipe and in the illustrated example, it is shown vertical to constitute a standard. It is to be understood that the elongated element 15 and the head 16 hereinafter described may be disposed horizontally, vertically, or at any intermediate angle. Steam passes from the elongated element 15 to a cylindrical head 16. In the connection between the standard 10 and the supply pipe 11 is a drain cock 14 to permit the water of condensation forming in the standard 15 and pipe 11 to flow to the standard 10 when the cock 14 is open. The head 16 is preferably circular or oval in cross section except at the supply end 17 to which the steam is supplied from standard 15. Other cross sections are however serviceable. Said end 17 presents a tapered zone for the ready movement of the fabric A to and along the head 16. Steam jets 18 are provided so that steam may escape from the hollow interior of head 16 to the exterior thereof. In the illustrated example I have shown two annular series of jet orifices 18 and each series is shown as leading to an annular external groove 19 formed in the head 16. The provision of the grooves 19 insures an even distribution of the steam about the fabric and also prevents the fabric A from closing or partially closing the jet orifices 18. Above the jet orifices 18 I form the head 16 with an annular external bead 20 which enlarges the tubular fabric annularly and provides a chamber directly beneath the bead 20 between the same and the jet orifices 18 in which steam may accumulate to insure that the steam is applied to the fabric over its whole internal surface. The said bead 20 furthermore acts to stretch the fabric and distend the same laterally which results in facilitating the movement of the tubular fabric over the major area of the head 16.

In the use of the device the head 16 is unscrewed from standard 15 and the tubular fabric is then placed on said standard 15. The head 16 is now replaced on the standard 15 and the fabric drawn forwardly over said head 16, the tapered zone 17 facili-

tating this step. The fabric may be drawn manually over head 16 or by any suitable means, a known arrangement of drawing rollers B being indicated in part in dotted lines in Figure 2. The standard 15 is in practice of a length to accommodate tubular fabrics of the maximum length for which the device is to be employed. Similarly, the head 16 above the bead 20, it will be observed, has substantial elongation so that the fabric remains on the head for a considerable period, the purpose being to partially dry the fabric by reason of the fact that said head 16 is heated to a substantial degree by the presence of the steam therein.

The device may be employed for shrinking a large tubular fabric as well as for stretching a comparatively small tubular fabric. This is so because when a large fabric is drawn over the head 16 and steamed, the steaming tends to give a shrinking effect.

Flat fabrics may be subjected to the stretching or shrinking action of the device by temporarily sewing the longitudinal side edges of the flat fabric to give it a tubular form.

To effect a steaming of the fabric both interiorly and exteriorly and especially having in mind thick fabrics, I provide an annular steam pipe 21 having a suitable inlet member 22 to receive connection with a steam pipe branch 24, and having at the inner periphery jet orifices 23 to direct steam radially inward against the exterior surface of the fabric. Said steam pipe 21 extends entirely about the head 16 and leaves room for the passage of the fabric between the same and the external surface of the head.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. In a device of the class described, a hollow head over which a tubular fabric may be drawn, said head adapted to receive a supply of steam and having jet orifices to permit the steam to pass from the interior to the external surface of the head, and a bead extending about the exterior of the head, said head beyond said bead being elongated to constitute drying means.

2. In a device of the class described, a hollow head over which a tubular fabric may be drawn, said head adapted at one end to receive a supply of steam and having jet orifices adjacent said end to permit steam to pass from the interior of the head to the external surface thereof; together with a bead extending about said head at the exterior, said bead disposed adjacent the jet orifices so that a steam space is formed between the jet orifices and the bead.

3. In a device of the class described, a hollow head over which a tubular fabric may be drawn, said head adapted to receive steam and form jet orifices in which the steam may pass to the exterior of the head, together with a bead on said head adjacent the jet orifices for distending the fabric laterally.

4. In a device of the class described, a head over which a tubular fabric may be drawn, said head adapted to receive a supply of steam and having jet orifices to permit escape of the steam to the exterior, for steaming the tubular fabric at the interior, and a steam pipe extending about the head and having jet orifices adapted to direct steam radially inward against the external surface of the fabric.

5. In a device of the class described, a head over which a tubular fabric may be drawn, and a steam pipe surrounding said head and having jet orifices for the escape of the steam at the inner periphery of said pipe.

MAURICE M. KASANOF.
